US0D1053721S

(12) **United States Design Patent** (10) Patent No.: **US D1,053,721 S**
(45) Date of Patent: **** Dec. 10, 2024**

(54) **BOTTLE**

(71) Applicant: **BEAUTE PRESTIGE INTERNATIONAL**, Paris (FR)
(72) Inventor: **Tokujin Yoshioka**, Tokyo (JP)

(**) Term: **15 Years**

(21) Appl. No.: **35/518,346**

(22) Filed: **Aug. 31, 2023**

(80) **Hague Agreement Data**

Int. Filing Date: **Aug. 31, 2023**

Int. Reg. No.: **DM/231242**

Int. Reg. Date: **Aug. 31, 2023**

Int. Reg. Pub. Date: **Sep. 15, 2023**

(30) **Foreign Application Priority Data**

Mar. 24, 2023 (EM) 015015656-0001

(51) **LOC (14) Cl.** **09-01**

(52) **U.S. Cl.**

USPC **D9/688; D9/529**
